ABSTRACT: A door opener utilizes the force developed by leverage on the jamb or frame of a door proximate its lockset to slip the door's latch out of its catch to enable the door to be pushed open. The door opener has a lever arm which is load coupled to a fulcrum arm and an extension arm for the application of the opening force. The extension arm is extensible from the lever arm to develop a mechanical advantage. The fulcrum arm's load coupling to the lever arm is at any of a number of longitudinal positions along the lever arm to accommodate different door widths while optimizing the mechanical advantage available with the device. Load transmitting members are eccentrically mounted at the ends of the lever arm and fulcrum arm to provide bearing for the transmission of a door opening load to the door jambs and adjustment for door width.

An alternate embodiment provides a door opener with a pair of load transmitting members to bear against opposite door jambs coupled together through a gear sector and a rack. Rotation of a handle secured to the gear sector produces movement of the load transmitting members against the door jambs for freeing the door's latch from its catch.

DOOR OPENER

BACKGROUND OF THE INVENTION

The present invention relates to a door opener for use by firemen, policemen and the like to open a locked door without damaging the door jambs, and, in particular, to a door opener which accommodates different size doors and which may be used for doors hung in wood or metal frames or jambs.

In emergency situations where access to a room is required by firemen or policemen, it has long been the practice to break down the locked door. Typically, the door is broken down by a fire ax. Obviously, this technique destroys the locked door, but it may have other adverse effects as well. For example, if access to a locked room is required to reach a stricken person, the noise of door destruction can create anxieties in his mind which could aggravate his condition.

But a nondestructive door-opening device must be light, small and easy to operate. If these requirements are not met, a door opener would find little application because of storage, transport and operation difficulties.

Thus there is a present requirement for a simple, light and easily operated device for opening locked doors without destroying them and which is easy to handle.

SUMMARY OF THE INVENTION

The present invention provides a light, small and easily handled door opener which utilizes the principle of leverage to obtain a significant mechanical advantage and allow the spreading apart of a door's frames or jambs to slip the latch of a door free of its catch.

In one form, the present invention contemplates a lever arm which is load coupled to a fulcrum arm and an extension arm for applying a load through the lever arm and fulcrum arm to the frames of a door. The lever arm has a first end and a second end, with the second end being adapted to transmit an applied load through a first load transmitting member pivotally mounted to the end. The extension arm is extensible from the lever arm to a plurality of extended positions. In any of these extended positions, the extension arm is capable of transmitting bending loads applied to it by a fireman or the like to the lever arm and, through the lever arm, compresses loads to the fulcrum arm. The fulcrum arm has an end pivotally secured to a second load transmitting member for the transmission of applied loads through the fulcrum arm to the fulcrum arm's load transmitting member and then to the door frame opposite the frame engaged by the load-transmitting member mounted on the lever arm. Load-coupling means, which may be a pin in the fulcrum arm, provides the load coupling between the lever arm and the fulcrum arm. This load-coupling means is received by means in the lever arm, for example, a plurality of longitudinally disposed and spaced-apart notches, for the transmission of a load applied on the extension arm through the lever arm and load-coupling means to the fulcrum arm.

In preferred form, the door opener of the present invention provides means for collapsing the door opener into a compact unit for purposes of storage and ease of handling. This may be accomplished, in part, by a spring clip in the lever arm which is engageable with the fulcrum arm when the latter is pivoted to the lever arm. The extension arm is collapsible into the lever arm by providing as a part of the lever arm an extension arm housing which may be in the form of a hollow, rectangular cross section beam welded to a U-shaped channel beam, the latter beam providing the loading-coupling means and the mounting for the lever arm's load-transmitting member. In order to provide for even more adjustment to accommodate different door frame widths while providing for door frame spreading, it is preferred to eccentrically mount the load-transmitting members at the ends of the fulcrum and lever arms. These eccentrically mounted load transmitting members have two bearing surfaces at right angles to each other. The eccentric mounting of the load-transmitting members, in con-

junction with these two bearing surfaces, effects the adjustment by the difference in distance between the bearing faces or surfaces and the pivot points of the load-transmitting members.

5 An alternate embodiment of the present invention contemplates the use of two load-transmitting members coupled together for expansion along their longitudinal axes through a rack attached to one member and a sector of a gear attached to the other member. The gear sector engages the rack and, 10 when rotated by a handle, moves the load-transmitting members against the door frames to expand them and free the latch from the catch. Preferably, the handle is foldable into one of the load-transmitting members when the door opener is collapsed for transit and storage. A sector is employed to 15 facilitate the quick adjustment of the two load-transmitting members by simply disengaging the teeth of the sector from the rack and pulling the two load-transmitting members apart or pushing them together.

20 The door openers of the present invention provide a simple and expedient way for firemen, policemen and the like to gain access into locked rooms without damaging the door frames or without disturbing occupants of the room. In either version, the door opener of the present invention is light and compact and is, therefore, readily transportable in fire and police vehicles, and can readily be carried by its potential user.

25 These and other features, aspects and advantages of the present invention will become more apparent from the following description, appended claims and drawings.

30 BRIEF DESCRIPTION OF THE FIGURES

FIG. 1 is a plan view, partly broken away, of a preferred embodiment of the door opener of the present invention inserted between jambs or frames of a door;

35 FIG. 2 is a view of the FIG. 1 embodiment taken along line 2-2 showing the telescoping facility of the extension arm into a box beam provided for it and for transferring bending loads applied to the extension arm to the balance of the lever arm, as well as the load-coupling means for coupling the fulcrum 40 arm with the lever arm;

FIG. 3 is a plan view, partly in section, of an alternate preferred embodiment of the present invention; and

FIG. 4 is a view, partly fragmented, taken along line 4-4 of FIG. 3.

45 DESCRIPTION OF THE PREFERRED EMBODIMENTS

The embodiment of the invention illustrated in the first two FIGS. will initially be described. This embodiment of the invention contemplates the use of leverage principles where the application of a relatively small amount of force to an extension arm produces a multiple of that force applied through a fulcrum arm and the lever arm to the frames of a locked door. This embodiment of the invention provides for the spreading 55 of the door frames under load by angular expansion of the load-transmitting arms.

The embodiment of the invention illustrated in the first two Figures includes a fulcrum arm 10, a lever arm 12 and an extension arm 14. The fulcrum arm is load coupled with the lever arm through a load-coupling pin 16. A load applied to the extension arm is transmitted to door frames by load-transmitting members 18 and 19. These load-transmitting members are pivotally carried by fulcrum arm 10 and lever arm 12, respectively.

65 The fulcrum arm is in the form of a box beam having a hollow interior. Load-coupling pin 16, as shown most clearly in FIG. 2, is secured in one end of the fulcrum arm. A load-transmitting member 18 is pivotally secured through a pivot pin 20 at the other end of the fulcrum arm. The top and bottom of the box beam fulcrum arm is cut away at this end, as indicated by reference numerals 22 and 24, to accommodate the pivotal movement of the load-transmitting member. Similarly, the load-coupling pin receiving end of the fulcrum arm is rounded at 26 for receipt in a U-shaped channel member 28 of the lever arm.

The lever arm is in two sections. The first section is the aforementioned U-shaped channel 28 which receives load-coupling pin 16. The second section is a box beam 30 coextensive in length with the first section. These sections are welded together at intervals along their length. The first section of the lever arm has longitudinal slots 32 and 33 along each of its sidewalls 34 and 36, respectively. The slots may be dispensed with to make a more compact door opener if their function of retaining fulcrum arm 10 with lever arm 12 by capturing pin 16 is not desired. Notches or recesses 38 and 40 are regularly disposed longitudinally along the bottom of the slots. In FIG. 1, sidewall 34 and its slot 32 and notches 38 are shown in the cutaway portion on the right of the Figure. The notches are sized to receive pin 16 and to transmit the load applied on the lever arm to the fulcrum arm. The notches are at a slight angle to the normal of the slot into which they open with the axes of the notches tending toward the longitudinal axis of fulcrum arm 10. This angulation is to provide for effective load coupling of the first section of the lever arm through pin 16 to the fulcrum arm by presenting a large bearing surface to the pin without the necessity of having relatively deep notches. The angled notches towards the right-hand side of the lever arm aid in retaining the fulcrum arm collapsed in the channeled first section 28 for storage, as will be described subsequently.

A spring clip 42, shown in the cutout portion at the left side of the first section of the lever arm, is attached to web 44 of section 28 and is disposed to engage fulcrum arm 10 through a hole 46 shown therein at its left end. Spring clip 42 has a U-bend 48 to overlie the wall of fulcrum arm 10 which bounds hole 46. Hole 46 and the spring clip are disposed such that pin 16 is capable of snug engagement in one of the extreme right-hand notches of the first section of the lever arm. This provides a convenient and secure way of storing and transferring the door opener, for the pin cannot lift out of its storing slot because the angle of sidewall on the short side of the slot prevents it.

Second section 30 of the lever arm receives extension arm 14 within its interior. This extension arm is in the form of a box beam. The second section is upset at 50 and 52 and the extension arm is expanded at 53 at its interior end 54 for the purpose of retaining the extension arm with the second section. Retention is effected because the expansion in the extension cannot clear the upsets in the second section. The second section of the lever arm can house the extension arm and the extension arm can telescope into and out of the second section. A bending load applied to the extension arm is transferred through expansion 53 to wall 56 of section 30, into sidewalls 34 and 36, and into the first section of the lever arm for transmittal to the door frames.

Load-transmitting members 18 and 19 of the present invention are illustrated in FIG. 1. Very simply, load-transmitting member 18 comprises a mounting boss 58, and bearing plates 60 and 62. The bearing plates are disposed at right angles to each other to provide bearing surfaces 64 and 66. Boss 58 is pivotally received on pin 20. Pin 20 is disposed closer to surface 64 than to surface 66; this provides an eccentric effect wherein rotation of one of the bearing plates at one side or the other affects the distance spanned by the door opener. Load member 19 is identical in its function and therefore will not be described in detail except to note that it is eccentrically and pivotally mounted through a pin 68 to the first section 28 of the lever arm. As with the fulcrum arm, first section 28 is cut away at 70 and 72 proximate pin 68 for pivotal movement of load-transmitting member 19.

The operation of the embodiment of the invention illustrated in the first two Figures will now be described. This description will be with reference to a physical embodiment of the invention. For clarity, a lock side door frame 75, complementary frame 77 and door 79 are shown. Initially, the door opener is in a collapsed position. In this position, pin 16 resides in one pair of the extreme right-hand notches 38, 40, and spring clip 42 engages fulcrum arm 10 with U-bend 48 bearing against the interior wall of the fulcrum arm. Extension

arm 14 is telescoped completely within second section 30 of lever arm 12. A fireman or policeman at the door will snap the fulcrum arm away from first section 28. Load transmitting member 18 on the end of fulcrum arm 10 is placed flush against door 79 and lock side door frame 75, as close to lock height as is physically permitted. The fulcrum arm is held essentially horizontal and at an angle of approximately 15° to 20° with respect to the plane of the door. This angle allows the load-coupling pin end of the fulcrum arm to be approximately 4 inches from the face of the door in one physical embodiment of the present invention. The other bearing load-transmitting member 19 is also placed flush against door 79 and on the inside of door frame 77 opposite the lock at a height essentially equal to the height of the complementary load-transmitting member. The load-transmitting members are therefore horizontal. Lever arm 12 is rotated until pin 16 is engaged in one of the slots or notches in the first section of the lever arm with its fulcrum point about 4 inches from the door. If a fine adjustment is necessary, either one or both of the load-transmitting members 18 and 19 may be rotated to present the desired bearing surfaces to the door frames. The extension arm is then slid out of the lever arm, say about two feet. A user such as a fireman then applies a force near the end of the extension arm directed as closely as possible to a perpendicular plane of the door. The resulting lever action forces the two load-transmitting members apart from each other to spread the door jamb until the latch of the lock is allowed to slip by its catch permitting the door to swing open.

30 The alternate embodiment of the present invention, shown in FIGS. 3 and 4, employs a leverage principle, as employed in the first embodiment, but utilizes a gear sector and a rack. This embodiment of the invention generally includes a first load transmitting member 80, a second load-transmitting member 82, a rack 84 having teeth 85, a gear sector 86 and a handle 88.

The first load-transmitting member is in the form of a box beam which is slotted at 90 along one longitudinal wall to provide a recess for handle 88. The slot defines a pair of opposed flanges 92 and 94. Rack 84 is secured on web 96 of the box beam load-transmitting member 80. The rack extends a substantial distance along the longitudinal length of this member. A bearing plate 97 closes one end of member 80.

45 Load-transmitting member 82 is essentially two parallel plates 98 and 100 which are secured together at either end by cross pieces 102 and 104. Crosspiece 102 also serves as a bearing plate for a door frame and thus complements bearing plate 97. These plates track in first load transmitting member 80, as is illustrated most clearly in FIG. 4. Thus they bear on inward extending flanges 92 and 94 and the extreme ends of web 96.

50 Gear sector 86 is semicircular and has a plurality of teeth 106 for engagement in complementary teeth 85 of rack 84. Handle 88 is secured to the gear sector as by clevis end 108 secured to a pin 110 which in turn is secured to the gear sector. This pin is journaled for rotation in plates 98 and 100.

The operation of the embodiment of the invention disclosed in FIGS. 3 and 4 will now be described. The door opener is 60 placed between door frames in a horizontal attitude as close as possible to the lockset. Any adjustment for door frame spacing is readily effected by rotating handle 88 clockwise to clear the gear sector's teeth from the rack and by extending or retracting the second load-transmitting member with respect to the first. When the approximately correct position is obtained, the handle is rotated counterclockwise to engage the gear teeth of sector 86 in rack 84. With continued counterclockwise motion of handle 88 in response to a force applied to the handle, the load-transmitting members elongate to expand the door frames and clear a door's latch from its catch.

65 When the door opener is to be stored, handle 88 is rotated clockwise to clear sector 86 from rack 84. The load-transmitting members are telescoped together. Handle 88 is folded into slot 90. The door opener is then in storage condition.

70 75 What I claim is:

1. A door opener for use by firemen and the like comprising:

- a. a lever arm having a first end, a second end and adapted to transmit a load to a door frame;
- b. an extension arm extensibly coupled to the lever arm to extend from the first end thereof into a plurality of extended positions and, while in an extended position, to transmit loads applied normal to the longitudinal axis of the extension arm to the lever arm;
- c. a fulcrum arm having a first end, a second end and adapted to transmit a load to a door frame;
- d. load-coupling means at the first end of the fulcrum arm to transmit a compressive load from the lever arm to the fulcrum arm while allowing angular movement between the two, the load-coupling means including a pin secured in the first end of the fulcrum arm;
- e. a plurality of notches disposed along a longitudinal length of the lever arm, each notch being sized to receive the pin and shaped to transmit loads from the lever arm to the pin;
- f. a first load-transmitting member pivotally connected to the second end of the lever arm having a bearing surface for engagement with a door frame to transmit a load thereto from the lever arm;
- g. a second load-transmitting member pivotally connected to the second end of the fulcrum arm having a bearing surface for engagement with a door frame to transmit a load thereto from the lever arm; and
- h. the first and second load-transmitting members each including a second bearing surface normal to the first men-

5 10 15 20 25 30

tioned bearing surface, the pivotal connection between the lever arm and the first load-transmitting member and between the fulcrum arm and the second load-transmitting member being eccentrically disposed between their respective bearing surfaces to provide for adjustment in door jamb spacing.

2. The door opener claimed in claim 1 wherein the notches are disposed at a slight angle from the normal to the longitudinal axis of the lever arm with their bases being closer to the second end than their mouths, and means on the lever arm and the fulcrum arm is provided to removably secure the fulcrum arm proximate its second end to the lever arm proximate its second end with the pin in one of the notches to thereby secure the fulcrum arm to the lever arm for storage.

15 3. The door opener claimed in claim 1 wherein the lever arm includes:

- a. a first section having two longitudinally extending, parallel sidewalls, the notches being in the sidewalls, the pin extending from either side of the fulcrum arm for receipt in the notches, and the fulcrum arm being capable of lying between the side walls of the first section for storage; and
- b. a second section rigidly secured to the first section, the second section defining a housing for the extension arm's storage and providing the load coupling of the extension arm and the lever arm for transmitting loads applied normal to the longitudinal axis of the extension arm to the balance of the lever arm, the extension arm being telescopically received in the second section.
